UNITED STATES PATENT OFFICE.

ANDREW J. CARTER, OF VICTOR, COLORADO.

HAMMER-DRILL.

1,115,898.

Specification of Letters Patent.

Patented Nov. 3, 1914.

Application filed December 23, 1912, Serial No. 738,140. Renewed March 28, 1914. Serial No. 828,096.

To all whom it may concern:

Be it known that I, ANDREW J. CARTER, a citizen of the United States, residing at the city of Victor, county of Teller, and State of Colorado, have invented certain new and useful Improvements in Hammer-Drills; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to hammer drills and may be said to constitute an improvement over the machine of my application Serial No. 661,288, filed November 20th, 1911.

The principal object of the present invention is to provide means for feeding water through the drill steel to the cutting face thereof.

Other objects will appear hereinafter as I proceed with that embodiment of the invention which for the purposes of the present application I have illustrated in the accompanying drawings, in which:

Figure 1 is a longitudinal, horizontal, sectional view showing the operating mechanism in plan with certain of the parts broken away. Fig. 2 is a vertical section taken approximately upon the line 2—2 Fig. 1, and looking in the direction of the arrow. Fig. 3 is a cross section upon the line 3—3 Fig. 1, looking in the direction of the arrow, the parts being shown upon a larger scale. Fig. 4 is a central longitudinal section taken upon a line corresponding to the line 4—4—, Fig. 3, and looking in the direction of the arrow. Fig. 5 is a detail end view of the striking surface of the hammer.

The same reference characters refer to like parts in each of the views.

Let the numeral 5 designate the cylindrical portion of the drill casing, which is closed at the ends by plates 6 and 7 secured to the cylindrical portion 5 by means of bolts 8, or other suitable fastenings. A removable cover 9, of a curvature corresponding to that of the casing, is mounted in the top thereof and near the rear end. Depending from the

bottom of the casing near the rear end is a sleeve 10 which is adapted to be connected with feeding means (not shown) for advancing the drill to the work.

Secured to the top and bottom of the casing are guide blocks 11 and 12 having V-shaped ways within which rides a hammer 13, having a rearwardly extending portion 14, upon which is pivoted at 15 a stem 16 having a T-head 17. Curved leaf springs 18 are secured upon the portion 14 of the hammer and bear at their extremities upon stem 16, tending to hold the latter in line with the axis of the hammer. A spiral spring 19 surrounds the stem 16 and bears at one end against the hammer 13 and at the opposite end against the partition 20. Partition 20 has a vertical slot 21 therein, through which stem 16 slides.

A transverse shaft 22 is journaled in bearings 23 which are split horizontally, the lower half of each bearing being in the casing and the upper half being in the cover 9, whereby the shaft may be lifted out of place when the cover 9 is removed.

Midway of its length the shaft 22 is formed into three U-shaped arms 24 extending radially at angles of 120 degrees, the arms 24 being adapted, upon rotation of the shaft 22, to engage the T-head 17 of the stem 16, and draw the latter rearwardly against the action of the spring 19. It will therefore be apparent that the blow delivered by the hammer 13 is due to the action of the spring 19, and that three such blows will be delivered for each revolution of the shaft 22. Also fixed upon shaft 22 is a spiral gear 25 which meshes with a second spiral gear 26, fixed upon the longitudinal shaft 27. Upon this rear shaft, near its end is fastened a gear wheel 28 which meshes with a gear 29 for imparting rotation to the drill steel, as will hereinafter appear. The shaft 22 is squared at 30 for the reception of a hand crank (not shown) by means of which it may be turned, though it should be understood that I do not limit myself to a hand driven drill as certain forms of power may be used to advantage, as will be well understood by those skilled in the art. The construction thus far described, except for cer-

tain minor details, is shown and described in my previous application above referred to and it is therefore considered unnecessary to describe the same more at length in the present specification.

Integral with the forward plate 6 are rearwardly extending arms 31 across the ends of which is mounted a flat bar 32 having a circular opening in the middle to form a journal for one extremity of the sleeve 33 which also passes through a circular opening of the same size in the plate 6. The gear wheel 29, above mentioned, is secured upon this sleeve 33 by means of a set screw 34.

15 The drill steel 35 is slidably mounted within the sleeve 33 but is prevented from turning therein by the lug 36 which is set into the steel 35 and engages a slot 37 in the sleeve. The steel 35 has a duct 38 extending axially from one end to the other, the duct being enlarged at its intersection with the rear face of the drill to form a socket 39 of spherical contour.

20 The spherical head 40 of a water conducting tube 41 is arranged to fit within the socket 39, the engaging surfaces being smooth to permit rotational movement. The tube 41 is threaded into a T-coupling 42, into the other openings of which are threaded shafts 30 43 and 44 forming together a rock-shaft which is mounted in journals 45 and 46, the shaft 43 having a collar 47 thereon, held in the desired position by a set screw 48. In the preferred embodiment of my invention 35 the shaft 44 is made in the form of a pipe and has a water hose 49 upon its outer extremity, leading from any source of water supply. Other forms of water connections may be employed, however, and in this respect I desire to limit my invention only 40 as indicated in the claims hereunto appended.

45 A spring 50 is coiled about the rock-shaft and bears at one end against the back of the tube 41 and at the opposite end against the casing 5 whereby the tube head 40 is held in engagement with the socket 39 at all times.

50 The hammer 13 has a socket 51 cut into its striking face, of a size and shape to surround the tube 41 and spherical head 40, when the hammer is in contact with the drill steel.

55 From the foregoing description the operation of my improved drill will be evident. Rotation of the shaft 22 serves to actuate the hammer and at the same time, by means of the spiral gears 25 and 26, shaft 27, and gears 28 and 29, to slowly rotate the sleeve 60 33 carrying with it the drill steel 35. Water is continually fed through the hose 49, pipe 44, tube 41 an opening leading from the spiral head 40 into the duct 38 and thence to

the cutting end of the drill steel, the spring 50 causing the head 40 to follow the drill 65 steel at each stroke of the hammer. The hose 49, being flexible, will permit of the slight rocking motion to which the pipe 44 is subjected by the reciprocation of the drill steel.

70 I claim as my invention:

1. In combination a drill steel having a water duct extending longitudinally therethrough, a pivotally mounted water conductor having an opening adapted to register with the rear end of said duct, a spring arranged to press said conductor against the rear surface of the drill, and a hammer having reciprocating motion only, said hammer having a recess in its striking surface 80 arranged to surround a portion of said conductor.

2. In combination a drill steel mounted for reciprocative and rotational movements, said steel having a water duct extending 85 axially therethrough, a pivotally mounted water conductor having an opening adapted to register with the rear end of said duct, resilient means for causing said opening and duct to remain in register during the reciprocation of the drill steel, and a hammer having reciprocating motion only, said hammer having a recess in its striking surface 90 arranged to surround that portion of the conductor which is within the path of the 95 hammer.

3. In a hammer drill, a drill steel, means for imparting thereto reciprocative and rotary motions, said steel having a water duct extending axially therethrough the rear 100 end of said duct being enlarged to form a socket of spherical contour, a pivotally mounted water conductor having a spherical extremity adapted to fit within said socket, said spherical extremity having an opening 105 adapted to register with said duct, and resilient means arranged to act upon the water conductor for holding its spherical extremity in position within said socket during the reciprocation and rotation of the drill steel. 110

4. In combination a drill steel having a water duct extending longitudinally therethrough, a tubular water conductor having one extremity in register with the rear end of said duct, a rock-shaft mounted at right 115 angles to the conductor, upon which the latter is secured, and resilient means acting upon the conductor to hold its said extremity against the rear face of the drill steel.

5. In combination a drill steel having a 120 water duct extending longitudinally therethrough, a tubular water conductor having one extremity in register with the end of said duct, a rock-shaft mounted at right angles to the conductor, upon which the latter is secured, said rock-shaft being hollow 125

and open at one end for connection with a water supply source, a joint between the conductor and hollow shaft having a water passage there through and resilient means 5 acting upon the conductor to hold its said extremity against the rear face of the drill steel.

In testimony whereof I affix my signature in presence of two witnesses.

ANDREW J. CARTER.
